US00D539830S

(12) United States Design Patent (10) Patent No.: US D539,830 S
(45) Date of Patent: * Apr. 3, 2007

(54) EYEWEAR

(75) Inventors: Davin Saderholm, Mission Viejo, CA (US); Robert Radi, Los Angeles, CA (US); Bjorn Jonsson, Rancho Santa Margarita, CA (US)

(73) Assignee: Arena Industries, LLC, Lake Forest, CA (US)

() Term: 14 Years

(21) Appl. No.: 29/229,821

(22) Filed: May 10, 2005

(51) LOC (8) CL. 16-06

(52) U.S. CL. D16/326

(58) Field of Classification Search D16/300-330, D16/101, 332-338; D29/109-110; D24/110.2; 351/41, 44, 51-52, 62, 158, 92, 103-111, 351/130, 61, 114-119, 121-123; 2/426-432, 2/447-449, 441, 436, 434-437

See application file for complete search history.
